UNITED STATES PATENT OFFICE.

WILLIAM McCONWAY, OF PITTSBURG, PENNSYLVANIA, ASSIGNOR TO THE
McCONWAY & TORLEY COMPANY, OF SAME PLACE.

CAR-COUPING.

SPECIFICATION forming part of Letters Patent No. 660,780, dated October 30, 1900.

Application filed April 30, 1900. Serial No. 14,865. (No model.)

To all whom it may concern:

Be it known that I, WILLIAM McCONWAY, a citizen of the United States, residing at Pittsburg, in the county of Allegheny and State of Pennsylvania, have invented or discovered certain new and useful Improvements in Car-Couplers, of which improvements the following is a specification.

The invention described herein relates to certain improvements in car-couplers of the Janney or swinging-hook type, and has for its object the provision of means whereby the hook or knuckle locking device may be held in inoperative position while the knuckle is closed, but will be released from such inoperative position by the opening movement of the knuckle.

The invention is hereinafter more fully described and claimed.

In the accompanying drawings, forming a part of this specification, Figure 1 is a sectional plan view of a coupler in locked position having my improvement applied thereto, the plane of section being indicated by the line I I, Fig. 3. Fig. 2 is a sectional elevation of the same in unlocked position, the plane of section being indicated by the line II II, Fig. 1; and Fig. 3 is a view showing the coupler-head in section and the knuckle and locking mechanism in elevation, the knuckle being closed, but unlocked.

My improved coupler consists of a head 1, knuckle 2, and swinging locking-block 3, said parts being constructed and arranged substantially as shown and described in application, Serial No. 6,236, filed February 23, 1900. As set forth in said application, the locking-block 3 is loosely mounted on the pin 4, passing through a box or shell 5, forming an upper side of the coupler-head, said box also serving as a stop or shoulder for limiting, by bearing on the end of the sill of the car, the inward movement of the coupler-head. The forward movement of the locking-block is limited by a suitable stop—such, for example, as that shown—consisting of a slot 8, formed in the bottom of the coupler-head in such position that a lug 7 on the lower end of the locking-block will enter said slot, and its movement will be arrested with the front wall

of the slot when the block has reached operative position in front of the tail of the knuckle. The locking-block is provided on its rear side with one or more fingers 11, with which a head 9 on the lifting-stem 10 is adapted to engage and shift the locking-block to unlocking position. The stem 10 extends up through the box or shell 5 and is adapted to be connected to any suitable form of mechanism whereby the coupler may be unlocked from the side of the car. These parts are so arranged that when the stem and head are raised they will engage hooks 11 and draw the locking-block back to unlocking position, as clearly shown in Fig. 3. In order to hold the locking-block in this position, the lifting-head 9 is provided with a prop or arm 12 at one end arranged to normally extend down at one side of the locking-block, and a shoulder or abutment 13 is formed on the coupler-head adjacent to the path of movement of the prop, so that when the head 9 is raised the prop or arm 12 will be shifted to one side onto the abutment or step 13. In order to insure the lateral movement of the lower end of the arm or prop, one of the hooks 11 is made a little shorter than the other hook, and the stem 10 is preferably formed at an angle to the head 9, so that when the head is raised it will be given a tip, as shown in Fig. 2, and thereby throw the lower end of the prop or arm out away from the locking-block and onto the step or abutment 13, and thereby support the locking-block in inoperative position. In order that the locking-block may be released, so as to engage the tail of the knuckle when the latter is closed, a shoulder 14 is so arranged on the tail of the knuckle that when the latter is open after being unlocked this shoulder will strike against the prop or arm 12 and push it off the supporting-step abutment 13, thereby permitting the locking-block to drop against the tail of the knuckle, so that when the latter is closed it will swing into operative position in front of the tail of the knuckle, as shown in Fig. 1.

It is preferred to so proportion the locking-block and the head 9 that when the head 9 is released and the locking-block swings to operative position the former will drop down

and wedge itself between the wall of the coupler and the rear face of the locking-block, thereby holding the latter firmly in locking position.

5 I claim herein as my invention—

1. In a car-coupler, the combination of a swinging hook provided with a tailpiece, a pivotally-mounted locking-block adapted to move automatically into the path of movement of the tail of the knuckle, means for shifting the locking-block to inoperative position, a shoulder or step on the coupler-head, an arm or prop adapted to be supported by the step and hold the block in unlocked position and means for shifting the lower end of the arm or prop laterally with respect to the coupler-head onto the step, substantially as set forth.

2. In a car-coupler, the combination of a swinging hook provided with a tailpiece, a pivotally-mounted locking-block adapted to move automatically into the path of movement of the tail of the knuckle, a shoulder or step in the coupler-head at one side of the path of movement of the tail of the knuckle, an arm or prop adapted to be supported by the step and hold the locking-block in unlocked position, and a shoulder projecting from the rear end of the tail of the knuckle and adapted to push the prop laterally with

respect to the coupler-head off of the step, substantially as set forth.

3. In a car-coupler, the combination of a swinging hook provided with a tailpiece, a pivotally-mounted locking-block adapted to move into the path of movement of the tail of the knuckle, a lifting-head adapted to shift the block to inoperative position, a step on the coupler-head, and an arm or prop on the lifting-head adapted to be shifted away from the locking-block onto the step when the head is raised, substantially as set forth.

4. In a car-coupler, the combination of a swinging hook provided with a tailpiece, a pivotally-mounted locking-block provided with fingers, a lifting-head adapted to engage the fingers on the locking-block, a step on the coupler-head, an arm or prop on the lifting-head adapted to be shifted onto the step when the head is raised, and a projection on the tail of the knuckle adapted when the knuckle is opened to force the prop off of the step, substantially as set forth.

In testimony whereof I have hereunto set my hand.

WILLIAM McCONWAY.
